H. G. GILLMOR,
ANTICREEPING DEVICE FOR RAILS,
APPLICATION FILED APR. 25, 1914.

1,281,341.

Patented Oct. 15, 1918.

UNITED STATES PATENT OFFICE.

HORATIO G. GILLMOR, OF WASHINGTON, DISTRICT OF COLUMBIA.

ANTICREEPING DEVICE FOR RAILS.

1,281,341.

Specification of Letters Patent. Patented Oct. 15, 1918.

Application filed April 25, 1914. Serial No. 834,349.

To all whom it may concern:

Be it known that I, HORATIO G. GILLMOR, a citizen of the United States, residing at Washington, in the District of Columbia, 5 have invented certain new and useful Improvements in Anticreeping Devices for Rails, of which the following is a specification.

My invention relates to devices for preventing the longitudinal creep of rails, such as are generally referred to as rail anchors, rail stays or anticreepers.

The object of the present invention is to provide a novel, simple and practicable device that will effectually grip and hold a rail against any tendency to creep longitudinally, the device comprising two parts, cheaply manufactured and readily applied to and removed from the rail, yet so constructed that, when in place, there is no chance of its being accidentally detached or deranged.

A further object is to provide an improved device, which firmly clamps both 25 sides of the rail base and presses upwardly upon the rail base with a pressure, which is distributed across the bottom of the rail base; and to provide resilience which will absorb vibration and take up looseness, due 30 to differences in expansion and contraction between the metal of the anchor and the rail, to slight retrograde movements or to other causes, to insure that the operative position of the parts upon the rail, essential to 35 its effectiveness, may be maintained under service conditions.

Two embodiments of the invention are set forth in the accompanying drawings, but it will be obvious from an inspection of the 40 claims forming part of this specification that the invention is not limited to the structures shown in the drawings.

Similar letters refer to similar parts in the drawings; in which:

45 Figures 1, 2, and 3 are, respectively, a section at the plane indicated by the broken line X in Fig. 2; a side elevation; and a plan view of the bottom; of one form of construction, showing the device in operative position on the rail.

Fig. 4 is a sectional view, showing the position of the parts when the dog is first placed in engagement with the rail.

50 Fig. 5 is a sectional view, showing one of the positions of the parts when the dog is being forced into position.

Figs. 6, 7 and 8 are, respectively, a sectional view, at the plane indicated by the broken line Y in Fig. 7; a side elevation; and a plan view of the top, showing a different embodiment of the invention.

Fig. 9 is an end view, partly in section, showing the position of the parts when the dog is first placed in engagement with the rail.

In the figures, A represents the ordinary railway rail mounted, as is usual, upon ties or sleepers, a portion of one of which is indicated by B. The anticreeping device consists of a base flange gripping member C and a horizontal and vertical pressure producing or clamping member D. The flange gripping member is formed with a portion E, engaging with the upper surface of the base flange of the rail and spaced portions 75 F lying below and at opposite sides of E 70 engaging with the bottom of the rail flange, a portion F' engaging surfaces of the bottom of the rail not directly below E, as clearly indicated in Fig. 3 where the outline of E 80 appears dotted. This has the advantage of permitting the part C to be produced as a casting without the use of cores. The flange gripping member is cambered or curved as indicated at G in Fig. 4; and, near the end 85 opposite to the portion E, there is formed a concave surface H and a convex surface I. The member C is symmetrical about the transverse plane and, on each side of this plane, there is formed a portion K, adapted 90 to lie against a tie or sleeper and present a considerable area of contact with the tie or sleeper. The horizontal and vertical pressure producing or clamping member D is constructed with surfaces L and M, complementary to the surfaces H and I on the member C and adapted to engage rotatably with these surfaces, and the other end has an arm O engaging with the upper surface of the rail base flange.

In using the device, the member C is placed upon the rail with E and F engaging with the base flange and is forced on to the rail, by blows of a hammer or otherwise, until the surface P comes into contact with the rail edge. One side of the rail base is thus clamped between the spaced portions F of the member C, which engage the bottom of the rail base, and the portion E, which engages the top of the rail base between the portions F. The cambering of the part C, as shown in Fig. 4, causes the

free end of the member C to stand off from the rail bottom. The position of the member C, after being driven into position, is indicated in Fig. 4. When the member C has been driven into position, the member D is placed with the surface L engaging with the surface H of the member C and rotated about the member C until the arm O comes into contact with the upper edge of the rail, as illustrated in Fig. 4. The member D is then forced into position and moves first angularly about the member C with surfaces L and H coacting; and, in so doing, a vertical pressure or pull is exerted upon the member C, the first effect of which is to deflect the cambered or curved portion G and bring it into contact with and to cause it to exert pressure upon the bottom of the rail base. This action distributes the pressure of C upon the bottom of the rail, so that all of the contacting portions of C are pressing upward upon the rail with pressures determined by the elastic strength of the material of which the member C is constructed and the pressure or pull exerted by the member D. At the same time, as a result of this forced angular movement of the member D, a transverse pull is also exerted by D upon C so that the pressure of the contacting surface P with the edge of the rail is increased. This transverse or horizontal pressure or pull is relatively large during that portion of the movement of D about C, in which the surfaces L of D and H of C coact. As the forced angular movement of D is continued, the engagement of D with C passes from contact of the surfaces L and H to contact of the surfaces M and I, as illustrated in Fig. 5, with a corresponding change in the character of the pressure or pull exerted by D upon C, the transverse or horizontal pull becoming relatively less and the vertical pressure or pull relatively more. During the further movement necessary to force D into place, the surfaces M and I coact and cause D, while exerting some transverse or horizontal pressure, to produce a relatively large vertical pressure, the effect of which is to draw the end of C firmly against the bottom of the rail causing the parts C and D to clamp the rail base rigidly between them. With the parts in operative position, as illustrated in Figs. 1 and 2, one side of the rail base is clamped between the portions E and F of the member C, the other side of the rail base is clamped between the member C and the part D and the member C is pressing upwardly with a pressure which is distributed across the bottom of the rail base. The rail base is thus very firmly gripped by the device and the engagement of the portion K of the part C with the tie B, which is firmly held by the ballast and earth in which it is embedded, effectually prevents longitudinal movement of the rail.

A somewhat different form of construction is disclosed in Figs. 6, 7, 8 and 9. In this embodiment of the invention the flange gripping member C is provided with spaced portions E' engaging with the upper surface of the rail base and a portion F' lying between and below the portions E' engaging with the bottom of the rail base. The end of the member C, opposite to the portions E' and F', is constructed with a convex surface H' and a concave surface I'. The part C is curved or cambered as indicated at G and provided with duplicate tie engaging portions K. The vertical pressure producing member, in this embodiment, differs from that described above only so far as is necessary to adapt this part to be used with the part C. It is provided with surfaces L' and M' complementary to the surfaces H' and I' of the part C; and, in being forced into position, moves angularly with the surfaces H' and L' coacting in the early movement and the surfaces I' and M' coacting in the later movement of the part D. It will be obvious that the device operates in substantially the same manner as that first described, in so far as the application of the parts and the clamping or gripping of the rail to prevent creeping is effected.

It will be noted that, in each form of construction above described, the shifting of the bearing, which involves a change in the angularity of relative movement between the two parts of the anchor, is in the nature of a camming action beneath the rail base, which produces a tightening of the anchor upon the rail.

From the foregoing it is believed that the construction, operation and many advantages of the herein described invention will be apparent to those skilled in the art, without further description; and it will be understood that various changes in the size, shape, proportion and minor details of construction may be resorted to without departing from the spirit or sacrificing any of the advantages of the invention.

Having thus described my invention, what I claim as new and desire to secure by Letters Patent, is:

1. A rail gripping element constructed with a three sided rail bottom engaging portion and an arm adapted to engage the upper surface of the rail base in spaced relation to all three sides of the base engaging portion.

2. A part for anticreepers constructed to engage and grip one edge of the rail base and to extend transversely beneath the rail base with a downward inclination toward the other edge of the rail base and provided with a seat upon the underside thereof of adjacent said other edge of the rail base adapted to engage a horizontal pressure producing member.

3. A rail engaging and clamping element constructed with a plurality of bearing seats adapted to successive rotational engagement with a vertical pressure producing element. 70
4. A rail embracing and gripping element for rail anchors constructed with a portion embracing one edge of the rail base and a portion extending transversely with a downward inclination toward the other edge of the rail, provided with a seat upon the under side of the end thereof adapted to engage with a vertical pressure producing member. 75
5. A rail base flange gripping part constructed to engage the top and bottom of the rail base at one side and provided with a transversely extending cambered portion having seats adapted to engage successively with a horizontal and vertical pressure producing element. 80
6. A dog constructed with a plurality of bearings adapted to successive rotational engagement with a rail gripping part. 85
7. A vertical pressure producing part constructed to engage the upper surface of the base flange of a rail and provided with convex and concave surfaces adapted to engage in succession with co-acting surfaces on a rail engaging part below the rail. 90
8. An anticreeping device for rails, comprising a rail gripping element constructed with a plurality of bearings and a device engaging said bearings in succession for effecting the gripping action of said element. 95
9. An anticreeping device for rails, comprising a rail engaging and gripping element constructed with a tie engaging portion and a plurality of seats and a rail engaging part constructed to engage said seats one after the other to effect the gripping action of said element. 100
10. An anticreeping device, comprising a transversely disposed rail embracing and clamping element provided with a tie engaging portion, a convex and a concave bearing seat and a rail engaging part adapted to engage and move angularly successively about said bearing seats to effect the clamping of the rail. 105
11. In an anticreeping device for rails, a cambered rail engaging and gripping element arranged to engage the top and bottom of the base flange at one side of the rail and a rail engaging device constructed to engage said element for drawing the cambered surfaces thereof into contact with the rail base. 110
12. An anticreeping device for rails, comprising a rail embracing and clamping element arranged to engage the base flange at one side of the rail and extend transversely beneath the rail with a downward flexure and a rotatable rail engaging part pivotally connected to said element for effecting the clamping action of the device. 115
13. In an anticreeping device for rails, a tie engaging rail gripping element having a downward flexure arranged for transverse disposition beneath the rail and a rail engaging device pivotally engaging said element for drawing the downwardly flexed element into contact with the rail bottom. 120
14. An anticreeping device for rails, comprising a rail engaging and gripping element, constructed with spaced portions engaging one face of the rail base flange and a portion between said spaced portions engaging the other face of the rail base flange, and a device pivotally engaging with said element and the rail for effecting the gripping action of said element. 125
15. In an anticreeping device for rails, a rail embracing and clamping element constructed with spaced portions engaging, at one side of the rail, one face of the base flange and an intermediate portion engaging, at the same side of the rail, the other face of the base flange and a rotatable rail engaging part engaging with said element for effecting the gripping action. 130
16. An anticreeping device for rails, comprising a rail engaging and gripping element arranged for transverse disposition beneath the rail and provided with portions at each side of the transverse plane adapted to engage with a tie and a rail engaging part pivotally engaging with said element for effecting the gripping action. 135
17. In an anticreeping device for rails, a reversible rail engaging and clamping part arranged for transverse disposition beneath the rail and a rotatable rail engaging element pivotally connected to said rail engaging part for effecting the clamping action. 140
18. In a rail anchor, the combination of two rail clamping elements, one of which has a tie abutting portion and one of which comprises a resilient bar extending under the base of the rail transversely thereof; and means for effecting an operative engagement between said elements and the rail which subjects said resilient bar to a bending strain. 145
19. In a rail anchor, the combination of two rail clamping elements, one of which has a tie abutting portion and one of which comprises a resilient bar extending under the base of the rail transversely thereof; and means for effecting an operative engagement between said elements and the rail which subjects said resilient bar to a bending strain in a direction upwardly toward the rail base. 150
20. A horizontal and vertical pressure producing part constructed with an arm adapted to engage with a rail base flange and a plurality of curved surfaces adapted to successive engagement with a rail base engaging member below the rail base. 155
21. In a rail anchor, the combination of two rail clamping elements, one of which is provided with a tie abutting portion and 160

- one of which comprises a resilient bar extending under the base flange of the rail transversely thereof and having a permanent set downwardly away from said rail base; and means for effecting an operative engagement between said elements and the rail which subjects said resilient bar to a bending strain upwardly toward the rail base.
- 10 22. An anticreeping device for rails comprising a tie engaging rail gripping element having a downward flexure arranged for transverse disposition beneath the rail and an angularly movable rail engaging part engaging said element below the rail for drawing the downwardly flexed element into contact with the rail bottom.
- 15 23. A rail engaging and clamping element constructed with surfaces on the under side thereof adapted to engage successively with surfaces of a horizontal and vertical pressure producing element whereby a camming action is effected between the elements.
- 20 24. An anticreeper for rails, comprising a rail gripping element constructed with a transversely extending bottom engaging portion having bearing surfaces thereon and a part engaging the rail base and said element, constructed with bearing surfaces so co-acting with those of said element that angular movement and camming action of said part in relation to said element produces horizontal and vertical pressure of said element upon the rail base.
- 25 25. A rail anchor comprising a rail base engaging part constructed with a tie engaging portion and bearing surfaces and a rail base engaging, pressure producing element, constructed with bearing surfaces so co-acting with those of said part that rotation of said element will effect a camming action and gripping of the rail by said anchor.
- 30 26. A device for preventing the creeping of rails, comprising a rail base edge and bottom engaging element constructed with convex and concave surfaces and a pressure producing part constructed with an arm adapted to engage the rail base and concave and convex surfaces so co-acting with the convex and concave surfaces of said element that said part may be forced into position by angular movement and thereby produce pressure, the horizontal component of which diminishes and the vertical component of which increases as the operative position of said part upon the rail is approached.
- 35 27. The combination of a railroad rail having a base, and a stationary part of a road bed, of an anticreeper adapted to engage said stationary part and comprising a resilient bar extending beneath the rail and having a part engaging the bottom thereof, one end of said bar having a rail gripping part engaging the top of one side of the rail base, a rail gripping part engaging the top of the other side of the rail base and provided with means operative to raise the other end of said bar, said bar being strained from a normal condition and exerting upward pressure against the bottom of the rail and pressing said rail gripping parts down upon the base of the rail in tending to resume said normal condition.
- 40 28. An anticreeper, comprising a resilient member extending beneath the rail transversely thereof and having one end adapted to grip one side of the rail base, means engaging the top of the other side of the rail base and the other end of said member operative to raise said end, whereby said member is subjected to a bending strain and caused to exert upward pressure upon the rail base, and means adapted to engage a stationary portion of the road bed.
- 45 29. A rail anchor, comprising a resilient element extending beneath the rail transversely thereof and having one end engaging one side of the rail base, a member engaging the other side of the rail base and the other end of said element operative to draw said end upwardly toward the rail bottom, whereby said resilient element is strained from a normal condition and caused to increase both the area of contact of said element with and the pressure exerted by said element upon the rail base, and means adapted to engage a stationary portion of the road bed.
- 50 30. A device for preventing the creeping of rails, comprising a resilient element extending beneath the rail, one end of which engages one side of the rail base, a clamping member, which clamps the other side of the rail base between said part and said element, subjects said resilient element to a bending strain and causes said element to exert upward pressure upon the rail base, and means adapted to engage a stationary portion of the road bed.
- 55 31. A device for preventing the creeping of rails, comprising a resilient element extending transversely under the rail and having at one end means which clamp one side of the rail base, a part which clamps the other side of the rail base between said part and said member and strains said resilient element from a normal condition, whereby said resilient member is caused to exert an increased pressure upon the rail and said pressure is distributed across the rail base, and means for engaging a fixed portion of the road bed.
- 60 32. A rail anchor, comprising a clamping member which embraces one side of the rail base, a resilient bar, one end of which intervenes between said member and the rail bottom and the other end of which engages the other side of the rail base, and means

adapted to engage a stationary part of the road bed.

33. A device for preventing the creeping of rails, comprising a clamping element which embraces one side of the rail base, a resilient bar, one end of which engages the other side of the rail base and the other end of which intervenes between said clamping element and the bottom of the rail, whereby said resilient bar is subjected to a bending strain and caused to exert upward pressure upon the rail base, and means for giving the device a fixed position in the road bed in opposition to the tendency of the rail to creep.

34. An anticreeper, comprising a clamping element which embraces one side of the rail base, a resilient bar which clamps the other side of the rail base and intervenes between said clamping element and the bottom of the rail, said resilient bar being strained and caused to exert an upward pressure which is distributed across the rail bottom, and means for engaging a stationary portion of the road bed.

35. An anticreeping device for rails, comprising a member which engages one side of the rail base and is provided with a resilient portion which extends transversely under the rail, means engaging the other side of the rail base and the end of said resilient portion operative to raise said end, whereby said resilient portion is strained and caused to exert an increased upward pressure upon the rail base, and means adapted to engage a stationary portion of the road bed.

36. A rail anchor, comprising an element which engages one side of the rail base and is provided with a resilient portion which extends transversely under the rail, a clamping member which clamps the other side of the rail base between said member and said element, strains said resilient portion from

a normal condition and causes said portion to exert upward pressure upon the rail base, and means for engaging a stationary portion of the road bed.

37. An anticreeper, comprising a member which clamps one side of the rail base and has a resilient portion which extends under the rail transversely thereof, a clamping element which clamps the other side of the rail base between said element and said member and causes said resilient portion to be strained and exert upward pressure which is distributed across the rail base and means for engaging a fixed portion of the road bed.

38. In a rail anchor, the combination of a tie engaging resilient element, having one end engaging one side of the rail base, extending under the rail transversely thereof with a permanent set downwardly away from the rail base, and a part which engages the other end of said element and the other side of the rail base and draws said resilient element into contact with the rail bottom.

39. In an anticreeper, the combination of a rail gripping member constructed to engage one side of the rail base and provided with a resilient portion, adapted to engage a stationary portion of the road bed, extending with a downward flexure under the rail transversely thereof and an element which clamps the other side of the rail base between said element and said member and causes the resilient portion of said member to exert an upward pressure distributed across the rail base.

In testimony whereof I hereunto affix my signature in the presence of two witnesses.

H. G. GILLMOR.
